Specification for Design.

Patented Aug. 22, 1922.

Application filed April 16, 1921. Serial No. 462,035. Term of patent 14 years.

To all whom it may concern:

Be it known that I, JAMES D. HILL, a citizen of the United States, and resident of Scottdale, in the county of Westmoreland and State of Pennsylvania, have invented a new, original, and ornamental Design for an Aviator-Operated Airplane, of which the following is a specification, reference being had to the accompanying drawing, forming part thereof.

My new design for an airplane is shown in

the accompanying drawings, in which,

Fig. 1 represents a bottom perspective view of an airplane embodying my design.

Fig. 2 represents a front view thereof on a reduced scale.

Fig. 3 represents a top plan view thereof.

I claim:

The ornamental design for an aviator operated airplane substantially as shown.

JAMES D. HILL.
